United States Patent Office.

CHRISTIAN W. QUANZ, OF NEW YORK, N. Y.

Design No. 2,571, dated February 5, 1867.

DESIGN FOR A CONFECTIONER'S CORNUCOPIA.

The Schedule referred to in these Letters Patent and making part of the same.

TO ALL WHOM IT MAY CONCERN:

Be it known that I, CHRISTIAN W. QUANZ, of the city, county, and State of New York, have originated and designed a new Confectioner's Cornucopia, of which the following is a full, clear, and exact description, reference being had to the accompanying drawings, making part of this specification.

This invention relates to a new and original design for a confectioners' cornucopia; and the invention consists in giving to the rim or mouth of such cornucopia an ornamental paper border, which in design represents lace or fancy needle-work, as hereinafter shown and described.

The drawings show a perspective view of my invention, in which A is the body of the cornucopia, constructed in the ordinary manner and having a ribbon bail or handle, C. To the rim *at* A I attach an ornamental border, B, which, in the drawing, represents point-lace or needle-work. This gives the article a more neat and finished appearance, and therefore adds materially to its pleasing qualities. The body A of the article, and the border B, may be constructed from a single piece of material, or the body may be constructed by itself and the border B attached thereafter, as found most convenient.

What I claim as my invention, and desire to secure by Letters Patent, is—

The design or pattern for the mouth of a confectioners' cornucopia, as herein shown and set forth.

CHRISTIAN W. QUANZ.
